UNITED STATES PATENT OFFICE.

ROBERT V. BINGAY, OF PITTSBURGH, PENNSYLVANIA, ASSIGNOR TO PITTSBURGH
TRANSFORMER COMPANY, A CORPORATION OF PENNSYLVANIA.

TRANSFORMER.

Application filed October 1, 1920. Serial No. 414,147.

To all whom it may concern:

Be it known that I, ROBERT V. BINGAY, a citizen of the United States, residing at Pittsburgh, in the county of Allegheny and State of Pennsylvania, have invented certain new and useful Improvements in Transformers, of which the following is a specification.

This invention relates to electrical transformers and particularly to small oil cooled transformers and tanks containing the same, immersed in oil. The object of the invention is to provide a transformer structure and tank that will be simple in form and 10 easily made up from standard stock.

In the accompanying drawings illustrating the invention—

Fig. 1 is a horizontal sectional view on line 1—1 of Fig. 2 showing one embodiment 20 of the invention, and

Fig. 2 is a vertical sectional view on line 2—2 of Fig. 1.

In the specific embodiment of the invention shown in the drawings a transformer 25 R supported in a frame F is contained together with the cooling oil in a tank T. The tank T is made up of sheet steel and is generally circular in horizontal section with its upper part 5 enlarged to overhang the lower portion 6 as indicated at 7. The lower portion 6 of the tank is formed by a steel sheet 8 cut to desired size, rolled into simple cylindrical form and welded together 30 at the meeting edges as along line 9. The upper part 5 of the tank is formed by a single steel strip 11 rolled into a circle of larger diameter than the lower portion 6 and also welded together at its meeting edges as at 12. This upper ring is assembled eccentrically on the lower part 6, being tangent thereto at 13 and overhanging at the opposite side 7. The upper end of the tank 6 extends into the ring 5 and a crescent shaped piece 15 is fitted in place between the 35 two circles and welded at its edges to both to form the bottom 14 of a bushing space 16 extending out over the lower portion of the tank.

Extending into this space 16 are the insulating bushings 17 and 18 for the high tension and low tension leads respectively and these bushings extend downward through holes 20 in the bottom piece 14 and are inclined to position their ends away 45 from the body of the tank. These bush- 50

ings are firmly set in place in cementitious material 21 poured into the space 16 and hardened. The top edge 22 of the ring 5 may be flanged over as shown for attachment of the tank cover 23 held by clamps 24. The bottom 25 of the tank is welded in place at the lower end of the part 6 and the tank is supported preferably by hanging as from a horizontal member m. For this purpose angle bars 26, 27 are bent to 55 fit the tank as shown and welded thereto in position with their lower ends under the bottom of the tank. These bars thus serve also as a base for the tank when standing on a support. Strap members 28, 29 are 60 adjustably bolted to bars 26, 27 and twisted as at 30, 31 so that their upper hooked ends will be aligned for engagement with the support m.

The simple circular formation of this 75 tank makes it easy to build from standard stock by simple bending and welding steps. There are no complicated shapes to be provided for nor remote corners nor difficult operations. The structure is especially 80 strong as it is formed by circular arches reinforced at the top and bottom, lying against the angle irons 26, 27 directly supporting the transformer frame F which is clamped down against the bottom by tightening of the nuts 35 threaded on rods 36 which are welded to the inside of the tank 85 as at 37.

The frame F is composed of metal strips 90 and angles cut from stock to fit the inside of the tank T. The vertical corners of the transformer core 40 are gripped by angle bars 41 fastened to horizontal angle bars 42 at the top and bottom and drawn together to clamp the core by bolts 43 through the ends of bars 42. Fastened to the lower angle bars 42 are the strips 44 forming the base of the frame resting on the bottom of the tank. Passing through the upper angle bars 42 are the angle members 45 provided with holes 46 for the bolts 36 and it is these angle irons 44 which receive the pressure of nuts 35 clamping the frame F down against the bottom of the tank. This frame structure provides a rigid clamping cage for the 105 transformer core supporting the transformer in fixed position in the tank secure against shifting in service. All parts of the frame are easily cut from standard metal stock and assembled and fastened together in 110

simple manner. The low tension leads 48 may be carried directly to and through the bushings 18 while the high tension leads 47 are looped through holes 49 in the spacer 5 strip 50 of insulating material extending across the top of the tank and held firmly in place by the wires 47. Rigid rods 51 pass through the bushings 18 and have the low tension leads connected to them at their 10 upper ends and their lower ends are connected to the outside circuits so that the conductors have solid binding posts fixed with relation to the transformer tank.

The transformer structure of this invention is neat and symmetrical in appearance and strong in construction with all its parts 15 permanently fastened against relative shifting. The weight of the transformer R is transmitted through the bottom 25 of the tank directly to the angle irons 26. Instead of being plain the vertical surface of the tank may be corrugated where desirable to give increased radiating surface by simply forming the corrugations in the sheet 20 8. While the invention has been explained in connection with an illustrative embodiment it is not confined hereto but is intended to cover such modifications thereof as fall within the scope of the appended claims.

30 I claim:—

1. In a transformer structure the combination with a tank having a lower circular portion and an upper enlarged portion eccentrically overhanging the lower portion, 35 of a transformer in said lower portion, and leads from the windings of said transformer passing downward through the overhang between said upper and lower portions.

2. In a transformer structure the combination with a tank having a lower circular portion and an upper enlarged circular portion eccentrically overhanging the lower portion, of a transformer in said lower portion, and leads from the windings of said 40 45 transformer passing downward through the overhang between said upper and lower portions.

3. In a transformer structure the combination with a tank having a lower circular portion and an upper enlarged portion overhanging the lower portion at one side and overlapping and tangent thereto at another, of a transformer in said lower portion, and

leads from the windings of said transformer passing downward through the overhang between said upper and lower portions. 55

4. In a transformer structure the combination with a tank having a lower circular portion and an upper enlarged circular portion overhanging the lower portion at one side and overlapping and tangent thereto at another, of a transformer in said lower portion, and leads from the windings of said transformer passing downward through the overhang between said upper and lower portions. 60 65

5. In a transformer structure the combination with a tank having a lower portion and an upper enlarged portion, of a transformer in said lower portion, leads passing 70 out through said upper portion, and an insulating strip spacing said leads and retained in place thereby extending across the top of said lower portion and projecting into said upper portion. 75

6. In a transformer structure the combination with a tank, of a transformer therein having leads for connection to the outside of said tank, outlet bushings for said leads in the upper part of the tank, and an insulating strip supported by the top of said tank and extending across the space above said outlet bushing and adapted to space said leads with relation to each other. 80

7. In a transformer the combination with 85 a double magnetic circuit core of a frame therefor comprising vertical angle bars fitting both surfaces of the corners of the core, horizontal angle bars fitting the ends and sides of said vertical bars and protruding 90 horizontally and clamping bolts extending between the ends of said horizontal angle bars and adapted to be set tight to hold the entire frame and core together. 95

8. In a transformer structure the combination with a tank having a body portion of sheet metal of a transformer in said tank and having a frame supporting the transformer core, cross members carried by said frame and extending beyond the sides thereof and means for holding said transformer against the bottom of said tank comprising bolt members welded in place within the body of said tank and extending inward to engage said cross members. 100

ROBERT V. BINGAY.
